[57] CLAIM

[21] Appl. No.: 790,572

The ornamental design for a rock crusher table liner, as
shown and described.

[22] Filed: Apr. 25, 1977

DESCRIPTION

[51] Int. Cl. ..... D15—99; D8—99

FIG. 1 is a perspective view of a table liner embodying
the features of our new invention, looking from above;
FIG. 2 is a perspective view of the table liner of FIG. 1
looking from the rear; and
FIG. 3 is a perspective view of the table liner of FIG. 1
looking from below.
